COVER FOR A HOOD COMPARTMENT OF
DROPHEAD MOTORCAR BODIESJohn Hewitt Orr, Coventry, England, assignor to
Carbodies Limited, Coventry, EnglandApplication October 24, 1949, Serial No. 123,240
In Great Britain October 25, 1948

3 Claims. (Cl. 296—37)

1

The invention relates to a body of a drop-head motor-car, of the kind which is provided with a compartment in the form of a well (which, in plan, is U-shaped—i. e., extending across the back, and partway round the sides of the passenger compartment) for receiving the head when lowered, the bottom edge of the head fabric (at least at the rear) being secured to a fixed, or to a retractable, waist rail adjacent the outer edge of the well, and the inner edge of the well at the rear being formed by the back of the adjacent seat, which latter can, in some instances, be hinged for movement forwardly out of engagement with a stop means.

It is the main object of the invention to provide means for improving the appearance of a body of the kind set forth when the head has been retracted into the well.

According to the present invention there is provided a cover, for the head-receiving well of a motor-car body of the kind set forth, including a rigid flap supported adjacent two opposite edges, respectively, from the seat back and from the outer edge of the well at the rear for bridging the rear of the well, the flap being movable into an uncovering position for enabling the head to be moved into and out of the well, and the flap serving as a shelf for the reception of small articles when the head is in the erected position.

The flap can be hinged at its forward edge (and on a horizontal axis) to, or adjacent the upper edge of the seat back so as to be movable to and from the position in which it bridges the top of the well, the rear edge of the flap, when the latter is in its bridging position, resting on the outer edge of the well at the rear.

Alternatively, the flap can be provided with one or more hinge elements for coaction with a like number of complementary hinge elements adjacent the outer edge of the well at the rear (the front edge of the flap being then adapted to rest on the seat back), the coacting hinge elements being of a kind which are readily separable and there being two sets of the said complementary hinge members of which one is inside the head and for use when the head is erected and the other is outside the head (with reference to the erected position of the head) and for use when the head is stowed.

Obviously, however, instead of using separable coacting hinge members the rear edge of the flap and the outer edge of the well at the rear could be provided with coacting elements of press-fastener devices or other readily separable attachment means, the said outer edge of the well,

2

as before, having two sets of the elements. Additionally, the forward edge of the flap could be attached in a similar way to the seat back.

Preferably the ends of the flap have upstanding ledges to prevent small articles from falling into the well at the sides thereof.

According to a further feature there are rigid side covers, for covering the well at the sides, which, when the head is lowered, are attachable at the rear to the said flap and are elsewhere attachable to the said body. When the head is erected, these rigid side covers can be stowed in the hood-receiving well.

Preferably the side covers are arranged for their rear ends to overlap the adjacent ends of the flap and those parts can be detachably connected together, as by fastening devices of the press-stud type.

According to prior U. S. specification No. 2,758,154, now Patent No. 2,529,458, granted November 7, 1950, there is provided, for a motor-car body of the type set forth, a head which includes a main hoop fast with the fabric portion and which is pivoted by its legs to the motor-car body, the legs of the hoop having an element of a locking means, for coaction with a spring-pressed latch supported within the well at the front, for holding the head erected. According to a still further feature of the present invention, the rigid side covers are equipped with lock elements (similar to those of the legs of the hoop) for coaction with the said spring-pressed latches when the hood has been lowered.

The flap and the rigid side covers can be made from any suitable material (e. g., from sheet metal so that a desired contour can be applied to them easily by quantity production methods) and, if desired, they can be garnished to suit the appearance of the remainder of the motor-car.

In the accompanying drawings—

Figure 1 is a perspective view of a portion of the interior, at the rear, of a motor-car body, with the head erected and showing the flap in the position in which it serves as a shelf;

Figure 2 is a sectional view, to a larger scale, on the line 2—2 of Figure 1;

Figure 3 is a perspective view, to a somewhat smaller scale than Figure 1, from the outside of the body with the head in its stowed position and covered by the flap, one of the rigid side covers being shown in position and the other one disconnected;

Figure 4 is a view corresponding with Figure 2 but drawn to a slightly smaller scale and illustrating a modified construction; and

55

Figures 5 and 6 show how each of the rigid side covers can be held in position by the spring-pressed latch of the said prior specification, the position of the main hoop of the head being shown in Figure 5, and the details of the spring-pressed latch in Figure 6.

Referring to the construction of Figures 1 to 3 the motor-car body 11 has a well extending behind the rear seat 12 and along the sides to the region of the rear edge of the door openings at each side, the rear part of the well being indicated at 13 and the side portions at 14.

As shown by Figure 2 the seat back is hinged at 15 to a stationary part of the body so that it can be swung forward as indicated by the chain dotted lines, the seat back having a stop 16 fast therewith for coaction with an abutment 17 fast with the body for limiting rearward swinging of the seat back.

The bottom edge of the head fabric, indicated at 18, is secured to the body 11 as by being trapped beneath a wooden waist rail 19 which is nailed in position, and some of the various hoops by which the head fabric is held erected are indicated at 20, being pivotally supported from the 20 body within the portions 14 of the well.

A rigid flap 21 is hinged at 22 to the top of the seat back so that when the head is in its stowed position the flap can rest on the waist rail (there being, of course, one thickness of the head fabric between the flap and the waist rail), there preferably being a resilient means, such as the spring 50, for holding the flap firmly down onto the waist rail. In this position of the head two rigid side covers 23 can be placed in position to cover the tops of the portions 14 of the well, the forward ends of these rigid side covers having means, presently to be described, for securing them in position, and their rear ends being adapted for securing to the ends of the flap 21 as by 30 press-fastener devices 24.

When it is desired to erect the head the rigid side covers are first removed and then the seat back is hinged forward to permit the flap to hinge downwardly towards the seat back (i. e., clockwise in Figure 2) the head is then erected in a normal manner and, after stowing the side covers in the well the flap is swung into the position shown in Figure 2, in which it provides a shelf for reception of small articles. For the latter purpose each end of the flap has an upstanding ledge 25 for preventing the articles from falling into the uncovered side portions 14 of the well.

In the construction of Figure 4 there is employed, instead of the hinged flap 21, a flap 21a having elements 26 of press-fastener devices at its forward and rear edges for alternative coaction with complementary press-fastener elements 27 or 28 on the seat back and 29 or 30 on the body at the rear of the well. When the head is erected the elements 26 are engaged with the coacting elements 27 and 29 to provide the shelf, and when the head is stowed the elements 26 are engaged with the coacting elements 28 and 30 to cover the rear of the well.

Referring to Figures 5 and 6 each of the limbs of an inverted U-shaped main hoop 31 of the head is fast with an arm 32 which is pivoted, through a hole 33, to the body within the adjacent portion 14 of the well. Each arm 32 has a bullet-nosed lock element 34 having a lateral notch 35. When the main hoop 31 is erected the element 34 passes through aligned holes of flanges 36 and 37 of a lock housing 38 fast with the body and the notch 50

35 is engaged by a spring-pressed latch 39 to hold the hoop erected.

According to the present invention, each of the side covers 23 is provided with a similar bullet-nosed member 40 having a lateral notch 41 for engagement by the spring-pressed latch 39 for holding it in position, the main hoop 31 together with its arm 32, of course, being accommodated within the well when the head is in its stowed position. The latch 39 thus serves a dual purpose.

What I claim as my invention and desire to secure by Letters Patent of the United States is:

1. For the body of a drop-head motor-car of the kind having a well, for receiving the head when lowered, which extends across the back and part-way round the sides of the passenger compartment, and of which the forward side at the rear is defined by the back of the adjacent seat, the head being foldable and mainly of a pliable fabric having its rear bottom edge fast with the body in rear of the well; a cover for the well comprising a rigid flap, elements of disconnectable fastener devices secured to said flap adjacent its forward and rear transverse edges, two parallelly-spaced sets of coacting fastener elements arranged transversely of the body on said seat back, two similarly parallelly-spaced sets of coacting fastener elements arranged transversely of said body to be fast with the latter at the rear of said well and respectively on opposite sides of the pliable fabric where the latter is made fast with the body, the rearward coacting fastener elements of each said set being for coaction with the fastener elements of said flap for securing the latter in covering relationship to the well when the head is in stowed position with the pliable fabric covering the forward set of coacting fastener elements which are fast with the body in rear of the well, and the forward coacting fastener elements of each said set being for coaction with the fastener elements of said flap for holding the latter in position to act as a shelf for small articles when said head is in the erected position and the rearward set of coacting fastener elements which are fast with the body in the rear of the well are thus outside the erected head.

2. A cover, according to claim 1 and for the head-receiving well of a motor-car body of the kind which is provided, with a head-supporting hoop which is pivoted to the body and provided with a locking element for engagement by a coacting locking element fast with the body for holding the head erected, a pair of separate rigid side covers for the sides of the well, means for removably attaching the rearward ends of said side covers to said flap, the forward end of each of said side covers equipped with an element of a locking means for engaging the said coacting locking elements, when the head is stowed, for attaching said side covers at their forward ends to said body.

3. For the body of a drop-head motor-car of the kind having a well, for receiving the head when lowered, which extends across the back and part-way round the sides of the passenger compartment, and of which the forward side at the rear is defined by the back of the adjacent seat; a cover for the well comprising a rigid flap, means for supporting the forward transverse edge of said flap from said seat back, means for supporting the rear transverse edge of said flap from said body at the rear of said well, said supporting means permitting said flap to be moved into an uncovering position for enabling said head

to be moved into and out of said well, and said supporting means being operative to support said flap as a shelf for small articles when said head is in the erected position, and an upward projection adjacent each end of said flap for preventing articles placed thereon from falling into the well.
